FIG. 1

FIG. 2

FIG. 3

Inventor

YATES FISHBACK

By Watson E. Coleman

Attorney

UNITED STATES PATENT OFFICE.

YATES FISHBACK, OF CARROLLTON, ILLINOIS.

URINAL.

1,386,696.

Specification of Letters Patent.

Patented Aug. 9, 1921.

Application filed September 29, 1920. Serial No. 413,494.

To all whom it may concern:

Be it known that I, YATES FISHBACK, a citizen of the United States, residing at Carrollton, in the county of Greene and State of Illinois, have invented certain new and useful Improvements in Urinals, of which the following is a specification, reference being had to the accompanying drawings.

This invention relates to urinals and particularly to a urinal for use by an invalid or person confined to bed.

An object of the invention is to provide a device of this character capable of being readily emptied, and which will not spill the contents unless disposed in a certain position.

Another object is to provide a device of this character so constructed that it will always be maintained upon its bottom and wherein the top of the container serves as a portion of the main conduit.

A still further object of the invention is to provide a device of this character having substantially triangular ends so that the upper portions of the sides as well as the top of the container serve as portions of the main conduit and wherein no removable parts such as caps or stoppers are necessary in order to permit the container to be emptied.

With the above and other objects in view, the invention consists in the improved construction and arrangement of parts to be hereinafter more particularly described, fully claimed and illustrated in the accompanying drawings, in which:

Figure 1 is a top plan view of a urinal constructed in accordance with an embodiment of the invention.

Fig. 2 is an end view showing the mouth of the container,

Fig. 3 is a longitudinal sectional view, and

Fig. 4 is a sectional view taken on the line 4-4 of Fig. 3.

Referring to the drawings, 5 designates a container having triangular ends 6 and 7, a broad bottom 8 and a narrow top 9. The top portion of the container includes a tubular extension 10 which serves as the mouth of the container. The lower end portion 11 of the extension is secured to the end 7 with an opening 12 formed therein closely adjacent the top 9. In this way, the top 9 of the container also serves as a portion of the mouth.

In order to prevent the contents of the container from becoming accidentally discharged, I provide a novel form of conduit

member consisting of a semi-circular trough or conduit member 13 which extends longitudinally and laterally of the container and is secured to each side thereof. The end 14 of the trough or conduit member is secured to the end 7 of the container in registration with the lower portion of the extension 10. It is then inclined downwardly toward the end 6 and has its end 15 disposed in spaced relation to the inner surface of the end 6. In view of the inclined position of the trough or conduit member 13, the same will permit the matter discharged into the container to readily flow to the end 6 and over the end 15.

Disposed within the container, is a second conduit member or trap 16 which is also constructed in the form of a semi-circular trough. The sides of the conduit member 16 are secured to the sides of the container while the end 17 is secured to the end 6 of the container in spaced relation to the end 15 of the conduit 13. The conduit member 16 is disposed in an inclined position, that is, it inclines from the end 16 toward the opposite end 7 of the container, the end 18 of the conduit member 16 terminating adjacent the intermediate portion of the container, in spaced relation to the bottom 8 and the lower surface of the conduit member 13.

In view of the novel arrangement of the conduit members 13 and 16 a substantially stepped or indirect conduit or passage-way is provided so that the matter discharged into the conduit 13 flows in one direction, over the end 15 and then is directed in the opposite direction, over the end 18 to the bottom of the container. The conduit member 16 is considerably shorter than the conduit member 13 so that the same does not interfere with the capacity of the interior of the container. At the same time the conduit member 16 prevents the matter in the container from accidentally flowing out through the extension 10 should the container be accidentally turned upon its sides so that accidental spilling is practically impossible.

To empty the container, the same is tilted so as to cause the matter therein to flow toward the end 7. The container is then inverted so that the bottom 8 is above the top 9 whereupon the conduit member 16 serves as a funnel to permit the matter to flow through the passage formed by the conduit member 13 and the top portion 9.

From the foregoing it will be readily seen

that this invention provides a novel form of urinal which, in view of its simplicity is sanitary in every respect as there are no detachable parts or closure means. At the same time it is compact in form, very convenient to use and cannot be accidentally upset in view of its triangular formation, and even if it is upset, it is necessary to maintain the upper end in a horizontal plane before the matter will be discharged, so that it is practically impossible to spill the contents of the container. The device is adapted for use by the male sex but it is obvious that the extension 10 may be altered to permit the device to be used by the female sex. I therefore do not wish to be limited to the specific embodiment of the invention described herein, inasmuch as many changes and modifications may be resorted to without departing from the spirit and scope of the claims.

What I claim is:—

1. A device of the character described comprising a container having a broad bottom and a narrow top, a horizontal tubular extension carried by the upper portion of the container, one end of the container having an opening registering with the tubular extension, a conduit member supported by the sides of the container and substantially registering at one end with the lower portion of said extension and the opening, said conduit member extending longitudinally of the container and having its opposite end disposed in spaced relation to the opposite end of the container and a second conduit member supported by the sides of the container and having one end secured to said last mentioned end of the container and having its opposite end terminating adjacent the intermediate portion of the container in spaced relation to the first mentioned conduit member and the bottom of the container.

45 2. A device of the character described comprising a portable container, a combined

inlet and outlet member formed in the upper portion of the container, one end of said member extending beyond one end of the container, the other end merging with the container, a conduit extending within the container from said end and terminating adjacent the opposite end of the container, and a second conduit member extending from the last mentioned end of the container and beneath the end of the first mentioned conduit, said conduit members being arranged to direct the liquid into and out of the container.

3. A device of the character described comprising a portable container having a combined inlet and outlet member in one end, a member disposed within the container adjacent the inlet and outlet member and co-acting therewith to provide a conduit, and a second conduit disposed beneath one end of the first mentioned conduit, whereby the lower surface of the first mentioned conduit and the top portion of the container receive and direct the liquid when the container is positioned to discharge the liquid therefrom.

4. A device of the character described comprising a portable container, said container having a narrow top and a relatively broad bottom, the sides of the container inclining from the bottom to the top, a combined inlet and outlet member projecting from one end of the container adjacent the top thereof, a conduit member extending from the inlet and outlet member and terminating inwardly of the container, a second conduit member extending from the opposite end of the container and terminating beneath the first mentioned conduit, whereby liquid within the container may be discharged therefrom upon the longitudinal rotary movement of the container to position the inlet and outlet member beneath the last mentioned end of the container.

In testimony whereof I hereunto affix my signature.

YATES FISHBACK.
